UNITED STATES PATENT OFFICE.

CARL C. BONN, OF SAN JOSE, CALIFORNIA.

DESIGN FOR A TICKET HOLDER.

Application filed April 12, 1926. Serial No. 17,248. Term of patent 14 years.

To all whom it may concern:

Be it known that I, CARL C. BONN, a citizen of the United States, residing at San Jose, in the county of Santa Clara and State of California, have invented a new, original, and ornamental Design for Ticket Holders, of which the following is a specification, reference being had to the accompanying drawing, forming a part thereof. In the drawing: The figure is a perspective view of a ticket holder showing my new design. I claim: The ornamental design for a ticket holder as shown.

CARL C. BONN.
